SERVING TRAY

Milton Putterman, Great Neck, N. Y., assignor to
All-Metal Stamping Corporation, New York,
N. Y., a corporation of New York

Application January 25, 1954, Serial No. 28,650

Term of patent 7 years

(Cl. D44—10)

To all whom it may concern:

Be it known that I, Milton Putterman, a citizen of the United States and resident of Great Neck, in the county of Nassau and State of New York, have invented a new, original, and ornamental Design for a Serving Tray, of which the following is a specification, reference being had to the accompanying drawings, forming part thereof.

In the drawings:

Fig. 1 is a perspective view of a serving tray embodying my new design.

Fig. 2 is a side elevational view thereof.

Fig. 3 is a cross-sectional view taken approximately on line 3—3 of Fig. 2.

I claim:

The ornamental design for a serving tray, substantially as shown.
